UNITED STATES PATENT OFFICE.

WILLIAM O. ROBBINS AND C. W. STAFFORD, OF NEW YORK, N. Y.

IMPROVEMENT IN MACHINES FOR PREPARING PAVING-BLOCKS.

Specification forming part of Letters Patent No. 97,553, dated December 7, 1869; antedated November 30, 1869.

To all whom it may concern:

Be it known that we, WILLIAM O. ROBBINS and CHARLES W. STAFFORD, of the city and State of New York, have invented, made, and applied to use a certain new and useful Improvement in Machinery for Preparing Wooden Blocks for Pavements; and we do hereby declare the following to be a full, clear, and exact description of the said invention, reference being had to the annexed drawings, making part of this specification, wherein—

Figure 1 is a general plan of the machine. Fig. 2 is a longitudinal section. Fig. 3 is a cross-section. Fig. 4 is an end view of the cutter-head and cutters for grooving the block and cutting off the angle. Fig. 5 is a perspective view of one block after it has been grooved on one side. Fig. 6 is a similar view of a block with the dovetail groove on both sides, and Fig. 7 represents a series of blocks united by longitudinal keys to form a section of pavement.

Similar marks of reference denote the same parts.

The object of this invention is to form in the sides of wooden blocks dovetail grooves, so that ranges of blocks can be secured together by wooden strips and form sections for paving, and the upper angles of the blocks are removed to form grooves in the surface of the pavement when the blocks are laid together. To effect this object the wood to form the pavement is first sawed into blocks by any ordinary means. Then the blocks are fed through our machine, which first brings them to a uniform thickness, and then the dovetail groove is made in one side by the action of cutters and the upper angle dressed off, as seen in Fig. 5. The opposite sides of the blocks are grooved, as seen in Fig. 6, when required, by passing them through a similar machine.

Our invention relates to the peculiarity of construction and mode of mounting the cutters that effect the grooving of the blocks and to the arrangement of mechanism for holding the blocks and presenting them to the action of the cutters.

In the drawings, *a* is the bed of the machine, supported upon suitable legs and standing in a horizontal position, as shown; or, to facilitate the delivery of the shavings and chips, the bed might stand up vertically, the other

parts remaining the same, except the weights that apply pressure to the feeding-rollers.

b b and *c c* are two pairs of feeding-rollers, the lower ones being level, or nearly so, with the surface of the bed *a*, the upper ones being supported by sliding boxes and kept toward the other rollers by weights or springs. We have shown the levers *d*, weights *e*, and slings or links *f* as the means for giving pressure by the upper rollers to cause the blocks of wood *g* to be moved forward regularly upon the bed *a* and between the gages or fences *h i*. The rollers *b b* and *c c* derive their motion from the shaft *h'*, belted to the shaft *k*, as shown by red lines in Fig. 2, from which a train of gears, as at *l*, connects with the lower rollers, and the rollers of each pair *b b* or *c c* are connected together, but the upper rollers allowed to rise or fall, and for this purpose gear-wheels are employed upon the shield-plates *m m*. These devices for giving motion to the pairs of rollers correspond generally with those employed on planing-machines. They therefore form no part of our present invention, and may be of any convenient character.

The rotary cutter *u* is mounted in a frame that is placed upon the bed *a* between the pairs of feeding-rollers. Said cutter is adjusted by the screws *u'*, so that the same can be raised or lowered to adapt the machine to different thicknesses of blocks.

At the side of the cutter *u*, next the rollers *c c*, the yielding presser *o* is fitted, so that the weighted levers *o'* act to force said presser upon the block of wood and hold it down against the action of the rotary cutters, and the presser *p* is fitted adjustably upon the other side of the rotary cutter-frame, and these two pressers *o* and *p* are sufficiently close to the point at which the rotary cutters operate to effectually hold the block to the bed and prevent the same being raised by the lifting action of the said cutters. This insures a uniform thickness in the blocks of wood that are fed along by the rollers *b b* and *c c*, the pressers *o* and *p* being closer together than it would be practicable to place the feeding-rollers. From the presser *o* the shield *2* rises and turns over the rotary cutter to direct the shavings as they are thrown off, and a similar shield, *3*, extends from the presser *p* over the upper roller, *b*.

The spring-fingers *r* and *s* are applied to hold

down the blocks of wood while being grooved and the angle beveled. The fingers *n* extend from the presser *p*, and the fingers *s* are attached to arms *s'*, that are adjustable in the stocks *t*. The blocks are pressed by the fingers 5 and 6 as they are moved along through the raceway, so as to keep the bases of the blocks against the fence *h*.

The tools that we employ for forming the dovetail groove consist of revolving saws or cutters that dress the inclined faces of the dovetail and cutting-tools that take out the intermediate material, so as to leave a smooth groove of the desired sectional shape.

The standard *u*² is fitted upon the bed *a* and provided with a stock, *v*, that can be raised or lowered by the screw 8, and this stock *v* is placed at right angles to a plane coinciding with one of the surfaces of the dovetail groove, and upon the stock *v* is a sliding frame, *w*, carrying the shaft *x* and cutter-head *y*; and *z* is a pulley, by means of which the shaft and head are rapidly revolved.

It will now be understood that the stock *v* can be raised or lowered according to the thickness of the blocks operated upon, and the frame *w* moved endwise to adjust the width of groove that is to be cut, and a nut and bolt, 9, are employed to clamp them firmly after adjustment.

The cutter-head *y* carries adjustable saw-sections 10, formed to dress off and smooth the side of the dovetail groove, and chisels or cutters 11 remove the wood from the middle portion of the groove and smooth the bottom thereof.

The standards *w*³, stock *v*³, shaft *x*³, cutter-head *y*³, and pulley *z*³ correspond in construction to those before named, except that the parts are handed or reversed, so as to stand on the opposite side of the line of blocks and a little to the rear of the cutter-head *y*, and dress off and form the other inclined surface of the dovetail groove.

The saw-sections 10 and chisel-cutters 11 can be removed for sharpening and adjusted to place as they wear, slots and screws being provided for that purpose.

The cutter-head *y* has a hub projecting at its end upon which cutters 13 are secured and adjusted, their ends being beveled, so as to remove the angle between the side and top of the block to form a groove when laid together.

It will now be understood that our machine

performs the following operations: First, the blocks are fed along successively; second, they are reduced to a uniform thickness; third, the dovetail groove is formed by saws and cutters acting on the two inclined faces to form the groove; fourth, the separate blocks are held firmly while under the successive operations, and the holding devices prevent any one of the blocks rising by the action of the tools or becoming displaced; fifth, the springs that act to keep the blocks to the fence *h* cause the dovetail cutters to act at a uniform distance above the base of the block, so that the keys can be driven in and the bottom surface of the section will be level.

In the pavement formed of blocks of wood united into sections by keys introduced into the dovetail grooves it is usual to leave the outside surfaces of the sections smooth. Therefore it will not be necessary to run all the blocks the second time through a machine of the character herein described for forming a second dovetail groove.

What we claim, and desire to secure by Letters Patent, is—

1. In a machine for dressing and grooving wooden paving-blocks, the combination of the following devices: first, a rotary cutter for reducing the blocks to a uniform thickness; second, mechanism for holding the blocks while being cut; third, mechanism for feeding the blocks through the machine; fourth, cutters for cutting crosswise of the grain of the wood and forming a dovetailed groove in the sides of said blocks; and, fifth, cutters 13 for removing the upper angle of said blocks, the parts being constructed, arranged, and operating substantially as and for the purposes set forth.

2. In a machine for grooving wooden paving-blocks, the combination of second, third, and fourth of the before-named devices for grooving the sides of pavement-blocks transversely of the grain of the wood, substantially as and for the purposes set forth.

In witness whereof we have hereunto set our signatures this 9th day of October, A. D. 1868.

WM. O. ROBBINS.
